PIPE RACK OR THE LIKE

Elliott V. Nagle, R.R. 3, Murrysville, Pa.

Filed July 22, 1964, Ser. No. 80,962

Term of patent 7 years

(Cl. D85—8)

The figure is a perspective view of a pipe rack or the like embodying my new design.

I claim:

The ornamental design for a pipe rack or the like, as shown.
